UNITED STATES PATENT OFFICE.

JAMES W. LAWHEAD, OF WILMINGTON, OHIO.

AIR PUMP.

Specification of Letters Patent. Patented Aug. 15, 1922.

1,425,663.

Application filed January 26, 1920. Serial No. 353,941.

To all whom it may concern:

Be it known that I, JAMES W. LAWHEAD, a citizen of the United States, residing at Wilmington, in the county of Clinton and State of Ohio, have invented certain new and useful Improvements in Air Pumps, of which the following is a specification, reference being had therein to the accompanying drawing.

10 This invention relates to air pump and has for its particular object to provide an air pump of improved construction which may be used either as an air compressor pump or as a vacuum pump, the construction and operation of the pump for the respective purposes being substantially the same, except as to the arrangement and operation of the valves.

An object of the invention is to provide 20 an air pump of the type above indicated, provided with improved valves, the valves as here shown being of the full gravity-action type in which all actuating mechanism is eliminated, the operation of the valves being responsive entirely in one direction to the suction impulses of the pump piston and the resulting air pressure thereon, and in the opposite direction to combined gravity and air pressure movement.

25 It is an object of the invention to provide valves that will retain their normal relation under all ordinary conditions of operation, that are cheap to manufacture and practically indestructible.

30 The type of pump here shown in which the invention in one approved form has been applied, is especially adaptable as a vacuum pump for automatic milking apparatus for dairy use. In pumps of well known construction of this general type in which ring-plate valves are used, difficulty has been experienced with the valves due to the twisting or warping of the rings, due to their light construction and relatively large size, 40 and to the action of the heat thereon generated by the air pump in operation.

In the construction here shown single-plate, full gravity-action valves are substituted for the ring-plate valves, and the 45 construction of the pump head and base in which the respective intake and discharge valves are located, is suitably modified to adapt the pump structure to the improved valve construction.

50 In the accompanying drawings: Fig. 1 is a side elevation, partially in lon-

gitudinal section of an air pump in which the improved valves have been applied;

Fig. 2 is a plan view of the pump head of the pump shown in Fig. 1, with part of the 60 cap plate cut away to show the relation of the valves relative to each other and the pump cylinder; and

Figs. 3 and 4 are a plan view and a detail longitudinal sectional view, respectively, of a modified construction of the 65 pump head.

The invention may be embodied in any suitable construction. As here shown, the air pump as a whole comprises a suitable 70 base casing 1, and pump cylinder casing 2; the casings being enlarged at their upper and lower ends, respectively, to form a crank shaft bearing 3, for the crank shaft 4, and having base flanges 5—6, whereby the upper 75 base is properly seated and alined, relative to the lower base, and secured thereto by bolts 7 extending through the flanges 5—6.

As here shown the crank shaft bearings are lined with sleeve bushings 8, and the 80 shaft is provided with a belt pulley 9, whereby power may be applied to the pump from any suitable source. Within the cylinder, the pump consists of the plunger 10, connected to the crank shaft in the usual 85 manner by a pitman 11, the construction shown being of a well known preferred form.

The head of the pump cylinder comprises a housing 12, cast integrally as here shown 90 with the pump cylinder casing, being substantially larger in diameter than the cylinder casing, and having a peripheral flange 13, formed at its upper end, which serves as the base for the cylinder head plate 14 and 95 cap plate 15, the parts being secured together by means of bolts 16.

The housing 12 has an annular depression or channel 17 formed therein, which is open to the end face of the cylinder casing, the 100 channel being normally closed by the cylinder head plate 14, which has a plurality of depressions or pockets 18 formed therein, communicating between the pump cylinder and the annular channel 17, and providing 105 clearance space and acting as a retainer for the valve plates 19. At its center the cylinder head plate is provided with an outlet port 20, normally closed by a gravity valve 21 whose upward movement is checked by 110 the boss 23 of the cap plate 15; air spaces 24, 25 and 26 being provided in the cap

plate whereby air discharged through the port 20 may be delivered from the pump through an aperture 27 or suitable pipe extensions connected thereto.

5 The housing 12 is provided as here shown with an intake port 28 which may be open to the atmosphere when the pump is used as a compressor, and may have any suitable connections with a vacuum tank or chamber, when the pump is used in connection with a vacuum system.

At its base the cylinder casing 2 may be provided as here shown with one or more exhaust valves, similar in construction to the intake valves in the housing 12, the exhaust valves consisting in the form shown of a valve housing 29, preferably cast integrally with the cylinder casing, and having a discharge aperture 31 formed therein; the aperture opening to the pump cylinder, and to the atmosphere at the top of the housing as shown by the opening 34 and being normally closed at its discharge end by a valve 32, under a cap plate 30 minimizing and providing clearance space and acting as a retainer for the valve plate 32 which normally closes the discharge end of the air passage 31.

From the foregoing detailed description 30 the construction and operation of the improved valves and the pump as a whole will be readily understood, the operation being as follows:

When the pump is used as an air compressor, the port 28 is open to the atmosphere. Upon the down stroke of the piston a vacuum will be formed in the cylinder and air will rush in through port 28, the pressure raising the valves 19, and the cylinder being 40 filled with air at atmospheric pressure. Upon the up stroke or working stroke of the piston the compression of air in the cylinder will cause valve 21 to open and valves 19 to close under pressure and the 45 air will be forced through the air passages in the cylinder cap plate and may be delivered through any suitable connections therewith to a pressure tank.

When the pump is used in connection with 50 a vacuum system, the port 28 is connected to the vacuum tank or chamber by suitable connections. Upon the down stroke of the piston air from the vacuum cylinder will flow to the pump cylinder until the pressure in 55 the respective cylinders, when the piston is in the down stroke, is equalized or substantially so, when the maximum vacuum state will be effected in the vacuum cylinder.

Upon the up stroke of the piston the valve 60 21 will open and valves 19 will close under pressure of the air in the cylinder, the operation in this respect being the same as when the pump is used as an air compressor, except that no pipe extensions will be used in 65 connection with the port 27 unless an air

pressure system is used in combination with the vacuum system which may readily be done.

The exhaust port valves at the base of the cylinder may be used with the pump either as 70 an air compressor or vacuum pump. Upon the down stroke of the piston the valves open and relieve the pressure within the lower portion of the cylinder. On the up stroke the valves close, thus causing the pressure 75 within the lower portion of the cylinder to become less than atmospheric pressure, which tends to balance the action of the piston by minimizing of the friction thereon. While the exhaust valves are a desirable 80 feature of the invention they are not essential to the successful operation of the pump, either as an air compressor or in connection with a vacuum system.

The exhaust valves furthermore are effective to prevent oil, which is liberally supplied in the lower part or oil sump of the crank casing to automatically lubricate the mechanism, from being forced, under great pressure which would otherwise exist in the 90 lower casing on the down stroke of the piston, past the piston into the discharge chamber of the cylinder and thence from the cylinder into the pressure tank or open atmosphere. While the reduced pressure in 95 the lower casing causes the oil to rise more readily in the casing on the up stroke of the piston, the relieved pressure on the down stroke is effective to minimize the escape of oil into the upper or discharge chamber of 100 the cylinder.

The modified form of the cylinder head shown in Figs. 3 and 4 is, in fact, the preferred form of construction. The gravity valves are lighter than the valve shown in 10 Figs. 1 and 2 and respond more readily to the discharge pumping action of the cylinder. Furthermore, the gravity members 35 of the valves are interchangeable with the corresponding parts 19 and 32 of the intake 11 valves and exhaust port, respectively. Thus, the construction of the pump as a whole is materially simplified and cheapened. It will be obvious from the illustration shown in Fig. 3 that the operation of the modified valves is substantially the same as the operation of the gravity valve 21, the air passages 36 and 37 serving the same purpose as the corresponding passages 24-25 and 26 in the construction shown in Fig. 1 and the passages 38 leading to the valves 35 serving the same purpose as the direct opening into the cylinder of the valve passage 20.

From the foregoing detailed description, the construction, operation and results of operation of the improved pump will be readily understood by those experienced in this art.

Having thus fully described my patent,

what I claim as new and desire to secure by Letters Patent, is:—

1. In an air pump, the combination, with a cylinder having near one end an inlet port and a valve therefor opening inward, an outlet port and a valve therefor opening outward, and having near the other end an outlet passage and a valve therefor opening outward, of a piston operating within the cylinder between said ports, whereby on the suction stroke air is drawn into the cylinder, on the reverse stroke air is forced out of the cylinder and whereby any air that leaks between the cylinder and piston is discharged through said outlet port when the piston is making its suction stroke, thus relieving the piston of back pressure.
2. In an air pump, the combination, with a structure comprising at one end a cylinder and at the other a closed chamber, an inlet port for the cylinder end with a valve closing outward, an outlet port at said end with a valve closing inward, and an outlet port from the chamber-end with a valve closing inward, of a piston within the cylinder portion and a crank shaft within the chamber-portion, whereby on the suction stroke air is drawn into the cylinder and any air within the chamber is essentially discharged therefrom.
3. In an air pump, the combination, with a structure comprising a cylinder at one end and a closed chamber at the other, an air

chamber having an inlet port and communicating with one end of the cylinder, valves 35 for said chamber opening inward, a plate having an outlet port with a valve opening outward, a passage from said chamber leading outward, and a valve therefor opening outward, of a piston in the cylinder and 40 crank shaft in the chamber, whereby air is drawn into and discharged from the cylinder and whereby also any air that passes the piston and enters said chamber is essentially discharged.

4. In an air pump, the combination of a cylinder having a piston operable therein, a circumferential air chamber 17 having intake ports 28, and an annular air channel leading into the cylinder near one end thereof, and gravity-action valves normally closing communication between said circumferential air chamber and said annular air channel, and a closed casing at the other end of the cylinder, an exhaust port communicating with this end of the cylinder through said casing, and a gravity action valve for said port, whereby upon operation of the piston air will be taken into the cylinder on one side of the piston through said 50 intake ports and annular air channel, and any air within the cylinder on the other side of the piston will be discharged to relieve the piston of back pressure.

In testimony whereof, I affix my signature. 65
JAMES W. LAWHEAD.
